UNITED STATES PATENT OFFICE

DONALD F. SPROUL, OF CHICAGO, ILLINOIS, ASSIGNOR TO CARDWELL WESTINGHOUSE COMPANY, A CORPORATION OF DELAWARE

DRAFT GEAR

Application filed October 30, 1929. Serial No. 403,418.

The invention relates to friction draft gears and is herein disclosed in connection with the Cardwell type of gear.

The improvement is in the form of the 5 guide ribs carried by a movable element of the gear and engaging longitudinal channels in the gear casings or chambered followers, the object of the invention being to secure freedom of movement of the parts under all 10 conditions of service.

The invention consists in a draft gear having a movable element cooperating with chambered followers and provided with guide ribs slidable within longitudinal channels in 15 the follower walls, the side walls of the portions of the rib being bowed.

In the accompanying drawing

Fig. 1 is a detail plan section of a portion 20 of the framing of a railway car, and of the draft gear embodying the invention; and

Fig. 2 is a sectional view on the line 2—2 of Fig. 1.

Portions of a pair of center or draft sills of a railway car are shown at 10, 11 and are 25 equipped as usual with draft and buffing lugs, one pair of which is shown at 12, 13.

The gear adopted for the disclosure of the present invention is of the Cardwell type and comprises a pair of chambered followers 14, 30 15; a set of wedging and friction developing elements housed within the followers, and spring means for resisting the compression of the gear. The wedging and friction elements as shown comprise two pairs of triangular wedge blocks 16, 17 and 18, 19 seated 35 respectively against the end walls of the followers 14, 15; a central wedging element 20 having its ends interposed between and co-operating with the triangular blocks of each 40 pair; and a pair of side wedging elements 21, 22 each engageable with the outer faces of one of the triangular blocks of each pair.

The resilient means for resisting the compression of the gear comprises a pair of helical springs 23, 24 mounted upon the ends of a tension bolt 25 extending transversely through the set of wedging elements, and the sills, the springs reacting between the outer seats, as 26, fixed upon the ends of the 50 rod and sliding seats as 27 mounted upon

the rod between the inner ends of the springs and the adjacent side elements 21, 22.

The central wedging element 20 is, as usual, provided with top and bottom guide ribs 28, 29 which slide within longitudinal channels 30, 31 formed respectively in the top and bottom walls of the followers 14, 15. 55

Heretofore, it has been the practice to make such guide ribs of uniform width, their side walls being parallel. The relative size 60 of the ribs and the channels has been such as to provide for a free sliding movement. In practice, distortion of the gear frequently occurs. Theoretically, the transverse faces of the two followers are normal to the axis of 65 the gear and the longitudinal movement of the various parts of the gear is parallel with such axis. In practice, however, tilting of the followers and oblique longitudinal travel of the various elements of the gear frequently occurs. These abnormal conditions 70 may be occasioned by improper placement of the lugs 12, 13 or to wear of the gear elements. When the two followers are out of alinement, or when for any reason the central wedging 75 element 20 is not perpendicular to the end walls of both of the followers, the straight guide rib binds within the channels, preventing free movement of the gear elements 80 and increasing the distortion of the gear. In the present invention, the side walls of the end portions 32, 33 are longitudinally bowed, as shown at 34, 35, permitting the tilting of 85 the element 20 relative to the axis of the gear without bringing the sides of the rib into binding engagement with the walls of the channels and permitting the gear to function in a normal manner even though it may have suffered some distortion. 90

I claim as my invention:

1. A draft gear comprising, in combination, a pair of opposed chambered followers each having longitudinal guide grooves in its top and bottom walls, a set of friction elements, a central member thereof extending into both followers and having top and bottom ribs slidable within the guide grooves, the sides of the end portions of the several ribs cooperating with the grooves of both followers being bowed. 100

2. A draft gear comprising, in combination, a pair of opposed chambered followers each having longitudinal guide grooves in its top and bottom walls, a set of friction elements, a central member thereof extending into both followers and having top and bottom ribs slidable within the guide grooves, both said ribs and grooves having engaging faces the engaging faces of one of the several interengaging elements being bowed.

10 In testimony whereof I affix my signature.
DONALD F. SPROUL.
